NO. 13,427

Nov 14, 1882

UNITED STATES PATENT OFFICE.

JOHN L. POPE, OF CLEVELAND, OHIO.

DESIGN FOR A CARRIAGE-STEP.

SPECIFICATION forming part of Design No. 13,427, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My invention relates to a design for carriage-steps; and its novelty consists in the ornamenting of the top surface of the plate or step in such a manner as to produce at about its center four Geneva crosses made integral with one another, and each connecting with another partially-formed cross.

In the accompanying photograph the four united Geneva crosses will be found marked with the letters *b b b b*, and it will be plainly seen that they are all formed of raised work, which is so disposed as to make one or more of the sides of each cross form a side or a part of an adjoining cross. From these united crosses the raised or ribbed work is extended out-

wardly and made to form the four other connecting partially-completed crosses, that I have 25 designated by the letters *c c c c*, and from the extremities of these latter figures, as well as the four crosses *b b b b*, the rest of the metal composing the plate is cast in solid form with the ornamental raised borders *d e*. The spaces between the figures *b* and *c* may be cast solid instead of open, as shown, and the raised ornamentation will still show in relief the distinctive features of my design.

What I claim as new, and desire to secure by 35 Letters Patent, is—

A design for a carriage-step, consisting of four united Geneva crosses, *b b b b*, and the four connected figures *c c c c*, substantially as shown and described. 40

In witness whereof I have hereunto set my hand this 31st day of May, 1882.

JOHN L. POPE.

In presence of—

A. A. POPE,
C. M. COPP.
